(57) **CLAIM**

The ornamental design for a textured front face wall block, as shown and described.

DESCRIPTION

FIG. 1 is a left-front perspective view showing the textured front face wall block of our new design;

FIG. 2 is a right-front perspective view thereof;

FIG. 3 is a front plan view thereof; and,

FIG. 4 is a top-front perspective view thereof.

The broken lines shown in the drawings depict the environment of the textured front face wall block and form no part of the claimed design.
